ATTORNEY

UNITED STATES PATENT OFFICE.

CHARLES T. PAYE, OF NORTH ATTLEBORO, MASSACHUSETTS, ASSIGNOR TO PAYE & BAKER MANUFACTURING COMPANY, OF NORTH ATTLEBORO, MASSACHUSETTS, A CORPORATION OF MASSACHUSETTS.

JEWELRY-MOUNTING.

1,177,893.

Specification of Letters Patent

Patented Apr. 4, 1916.

Application filed December 30, 1914. Serial No. 879,669.

To all whom it may concern:

Be it known that I, CHARLES T. PAYE, a citizen of the United States, residing at North Attleboro, in the county of Bristol 5 and State of Massachusetts, have invented certain new and useful Improvements in Jewelry-Mounting, of which the following is a specification.

My invention relates to articles of jewelry 10 and consists particularly of an improved method and means for mounting ornamental heads, gem-settings or the like on hat-pins, scarf-pins, girdle-pins and other similar articles.

15 The object of my improvement is to simplify the construction and cheapen the cost of manufacture of the article while enhancing its artistic appearance.

The manner and means for carrying out 20 the improvement are fully described in the following specification, illustrated by the accompanying drawing, in which:—

Figure 1 is an enlarged, perspective view 25 of my improved mounting shown in its simplest form as applied to a stem or pin; Fig. 2 is an enlarged, cross-sectional view of the same, illustrating the constructional features; Fig. 3 is an enlarged, perspective view of the pin and its attached seat-member 30 to which the ornamental part is secured; Fig. 4 is a perspective, detail view of the main or essential mounting-element in its simplest form; Fig. 5 is an enlarged, sectional view of another form of mounting 35 adapted to serve as a setting for faceted gems; Fig. 6 is a smaller view of another, more ornamental form of the mounting; and Fig. 7 is a cross-sectional view of the mounting shown in Fig. 6.

40 Heretofore it has been the usual practice in manufacturing pins or like articles of jewelry with ornamental heads to construct the ornament as a separate, complete element and to then attach it to the pin or stem either by soldering it thereto or swaging it thereon. Generally the ornamental part of the article, which in some cases might take the form of a gem-setting, is constructed of precious metal while the pin 45 or stem is of steel so that it is impracticable to solder the two together. For this reason the expedient has been generally adopted of soldering to the ornamental part of the pin what is known as a "French" head, or

in some instances a short section of small 55 tubing is attached in the same manner. The steel stem or pin is then inserted into the hollow head or the tubular extension of the ornament, as the case may be, and is secured in place by swaging the head or 60 tubing around it. With my present improved construction I do away with the "French" head or tubular extension on the ornament and secure the stem or pin in place without any swaging operation. To 65 accomplish this simplification in the construction and method of manufacture of the article I have devised an ingenious arrangement of the parts of the same as now described.

70 Referring first to Fig. 3, P designates the steel stem or pin to the end of which it is desired to apply an ornament such, for instance, as a gem setting. To the butt end of the stem P, I first attach a relatively 75 thin plate or seat-member D which as here shown takes the form of a circular disk. Any other form of member D may be used to correspond with the conformation of the setting itself, such as an oval, square, hexagon or other polygonal shape, the form here shown being the simplest to illustrate. The seat-member D is preferably soldered 80 to the end of the stem P, or in some cases it might be struck-up as an integral part of 85 the pin or shank on which the ornament is to be mounted. Referring to Fig. 2, the gem or ornament G is set in place with its bottom or flat face g abutting the top of the plate D, and usually it is of such dimensions as to slightly overlap the plate 90 around its edge.

To secure the gem in position I now apply the flanged member C to the pin, this being constructed in the form shown in Fig. 4. As 95 here illustrated the member C is made in the form of a cup-like disk or washer having an upturned rim or flange c and a central opening or pierced hole c'. Preferably, the stock around the hole c' is punched outward 100 to form a narrow, curved flange or fillet-like lip c² which gives a neater and more finished appearance to the pin when the member C is placed on the stem P as shown in Fig. 2. Another object of this forming or curling 105 of the metal outward from the hole c' is to insure a close fit for the member C against the bottom of the plate D. That is to say, if

there is any slight roughness or accumulation of solder around the joint of the pin P on the plate D the rounded edge of the hole c' will provide a clearance space so that the member C will not be prevented from being set up close against the bottom of the plate. It will be understood from reference to Fig. 2 that the stem or pin P is inserted through the opening c' in the member C and the latter is then carried up against the plate D. With the gem G in place on the top of the plate D the rim c of the member C is next bent in or formed over the beveled edge of the gem in place against the top of the plate 15 gems or jewels in their settings. When the parts are thus assembled the member C holds the gem in place against the top of the plate D, and the seating-member itself is also securely fastened to the plate and in this way 20 secured to the stem or pin P. Through this arrangement a particularly secure setting and strong joint-structure is provided and a very neat and finished appearance given to the whole article. It will be observed that 25 the soldered joint between the plate D and pin P is entirely covered up and concealed while the connection between the pin P and member C is given a particularly neat and finished appearance. It is also to be noted 30 that no tubular connection is required between the ornament and the pin, and therefore no swaging operation is necessary in assembling the parts.

In Fig. 5 I have illustrated a somewhat 35 similar ornamental mounting on the pin P, but in this case the setting for the gem S is made of concave form to adapt it to receive a faceted stone cut with a more or less pointed under side. That is to say, the seat-member E is made in the form of a conical cup 40 adapted to conform to the convex under side of the stone S, and the fastening member B is also of a corresponding concavity to adapt it to fit snugly against the outer surface of the member E. As in the previously 45 described arrangement the seat-member E is usually soldered to the end of the pin or stem P. In this case, as with the simpler form, the member B has a flanged rim or lip 50 b adapted to be turned over the edge of the stone S or, if desired, a plurality of prongs could be formed on the rim of the member B to be bent down against the upper facets of the stone to secure it in place in the usual 55 manner.

Figs. 6 and 7 illustrate a somewhat more elaborate embodiment of the invention in which the mounting itself forms the chief ornament and the gem is added as a further 60 embellishment. In this modification the flat seat-member D is applied to the end of the stem P as in the first-described arrangement, while the member F is constructed in the form of an enlarged, ornamental, shell-like head. The head or ornament F may be of

various and sundry shapes and configurations according to current styles, or individual tastes, the embodiment here shown being of a conventional design. As here illustrated it takes the form of an inverted bell 70 having its surface ornamented with artistic designs in relief. At its top the metal of the shell is formed inward to provide an interior, annular seat or shoulder f adapted to abut the under side of the seat-member D. 75 Above the shoulder f is an upstanding rim or lip f' adapted to be bent over the edge of the gem G and serving the same purpose as the flange c on the member C as previously described. With the parts assembled as 80 shown in Fig. 7 the gem G is held securely in place against the seat-member or plate D while the main element or ornamental head F is also secured to the seat D with its lower, reduced end f² surrounding the stem 85 P, and partly supported thereby. It is to be understood, however, that the head F is secured to the pin P solely through its engagement with the seat-member D and no soldering or swaging is required at its end f². 90

In place of the jewel or gem here shown any other suitable ornament might be set in the head of the pin, such as a medallion or cameo. The same method of construction can also be applied to ornamental heads in 95 which a metal top is substituted in place of the gem or jewel. In fact, numerous other modifications might be made in the ornamental features of the article without affecting its structural design. 100

It is to be noted that the several parts of my improved mounting are extremely simple in form and structure and therefore can be manufactured at a minimum cost. Their assembling requires practically but one mechanical operation, that of soldering the seat-member in place on the stem, so that the labor cost of production is also slight. By eliminating the tubular connection between the ornament and the pin I avoid the swaging operation usually required to fasten the parts together and also obviate the soldered joint on the ornament itself. Since the seat-member is entirely covered up and concealed it can be constructed of steel or of some base-metal which is easily joined to the steel pin and for this reason the joint will also be more secure. Besides being adapted for use on pins, my improved mounting can also be applied to other wire-like stems or shanks, 115 on such articles as bracelets, rings or other jewelry. 120

Various modifications might be made in the form and construction of the parts of my device without departing from the spirit 125 or scope of the invention; therefore, without limiting myself to the exact embodiments shown and described,

What I claim is:—

1. In an ornamental mounting for articles 130

of jewelry, the combination with a pin-stem, of a seat-member fast on the end of the stem, an ornament arranged with its bottom seated against the top of the seat-member, and a flanged cup-shaped member inclosing the seat-member and abutting its under side with the stem projecting through its bottom, said cup-member having its flange bent over the edge of the ornament to draw the latter down against the seat-member to force said seat-member against the cup-member and thus permanently secure all of the parts together in fixed relation.

2. In an ornamental mounting for articles of jewelry, the combination with an elongated stem, of a relatively flat plate fastened to the end of said stem, a flanged cup-shaped member formed with a hole through which the stem is inserted to bring the cup-member into position abutting the under side of the plate, and an ornament arranged with its bottom face seated against the top of the plate with the flange of the cup-member bent over its edge to secure the ornament in place while also causing the ornament to hold the cup-member pressed against the bottom of the plate to permanently secure all of the several parts together in fixed relation.

3. In an ornamental mounting for articles of jewelry, the combination with a gem, of a seat-member shaped to conform to the bottom face of the gem, a stem having its end fixedly secured to the bottom of the seat-

member, and a cup-member pierced with an opening to adapt it to be slipped over the stem to bring it into position abutting the under side of the seat-member and completely inclosing the latter, said cup-member having its flange bent over the edge of the gem to draw the latter down against the seat-member while causing the gem to hold the seat-member against the bottom of the cup-member to permanently secure all of the parts together in fixed relation.

4. In a gem mounting for articles of jewelry, the combination with a pin-stem, of a plate of base-metal soldered to the end of the stem; and a flanged cup-shaped member having an opening in its bottom to adapt it to be slipped over the pin-stem to bring it into position abutting the under side of the seat-member and completely inclosing the latter, said cup-member arranged with its flange bent over the edge of the gem to draw the latter down against the seat-member to force said member against the bottom of the cup-member, whereby the parts are rigidly secured together in permanent relation with the seat-member entirely hidden from view.

In testimony whereof I affix my signature in presence of two witnesses.

CHARLES T. PAYE.
